UNITED STATES PATENT OFFICE.

ERNST SCHALL, OF HARTFORD, CONNECTICUT.

DESIGN FOR A SPOON OR FORK.

SPECIFICATION forming part of Design No. 20,584, dated March 17, 1891.

Application filed January 27, 1891. Serial No. 379,327. Term of patent 3½ years.

To all whom it may concern:

Be it known that I, ERNST SCHALL, a citizen of the United States, residing at Hartford, in the county of Hartford and State of Connecticut, have invented and produced a new and original Design for Spoons and the Like, of which the following is a specification, reference being had to the accompanying drawing, forming part thereof.

10 The figure is a plan view of a spoon, showing my design.

The leading figure of my design consists in the pictorial representation of an oak-tree, showing a hole in the trunk of the tree, this view being stamped, etched, or engraved on the inner surface of the bowl *a* of the spoon.

15 The handle (denoted by *b*) terminates in a broadened portion, on which is depicted the seal of the city of Hartford, that consists of the pictorial representation of a hart. The edge of the handle at the broadened portion is ornamented by a foliage of oak-leaves, while a branch of the oak is twined about the shank of the handle, and in the spaces between the points crossed by this branch *c* are 20 dates indicating the date of hiding the char-

ter, of finding the same, and of the destruction of the original Charter Oak tree.

Beneath the figure of the hart on the broadened portion of the handle there is a space 30 or panel in which a word or phrase may be displayed; but my design consists, mainly, in the picture of an oak that is displayed in the bowl of the spoon, the picture of the hart on the broadened portion of the handle, and the 35 oak leaves and branches twined about the same and more or less conventionally arranged.

On the handle portion of the spoon panels or relatively-clear spaces are provided between the foliage for the reception of dates.

What I claim is—

The design for a spoon or the like herein shown and described, the same comprising the bowl having the picture of the oak-tree 45 and the handle intertwined with the foliage of the oak and displaying the picture of a hart, as set forth.

ERNST SCHALL.
